Attorney

UNITED STATES PATENT OFFICE.

GEORGE W. WASHINGTON, OF COLUMBUS, MISSISSIPPI.

FLOAT-OPERATED CIRCUIT-CLOSER.

1,343,947.

Specification of Letters Patent. Patented June 22, 1920.

Application filed August 1, 1916. Serial No. 112,543.

To all whom it may concern:

Be it known that I, GEORGE W. WASHINGTON, a citizen of the United States of America, and resident of Columbus, in the county 5 of Lowndes and State of Mississippi, have invented certain new and useful Improvements in Float-Operated Circuit-Closers, of which the following is a specification.

This invention relates to signals and particularly to devices for use in connection 10 with railways and more particularly for use on bridges, trestles and structures which are apt to collapse and effect the trackage of railways.

15 An object of this invention is to provide novel means for signaling when the depth of water over which the track is supported has risen to the point of danger which would menace the support for the track as where 20 high water is present and flowing through a bridge, it being the purpose of the inventor to signal when the water has reached a predetermined height or level.

25 A further object of this invention is to provide means for sending current to signals at opposite ends of the bridge or guarded structure, or to stations distant from the bridge.

30 With the foregoing and other objects in view, the invention consists in the details of construction, and in the arrangement and combination of parts to be hereinafter more fully set forth and claimed.

35 In describing the invention in detail, reference will be had to the accompanying drawings forming part of this specification wherein like characters denote corresponding parts in the several views, and in which—

40 Figure 1 illustrates a view in elevation of a bridge structure with a track showing the installation of the signal controlling means thereon;

45 Fig. 2 illustrates a view in elevation of the interior of the signal controlling means;

Fig. 3 illustrates a sectional view approximately centrally of the device shown in Fig. 2;

In these drawings 7 denotes a bridge struc-

ture which may be of ordinary construction, 50 the same having casings 8 thereon at such height as would be regarded as the high water mark, the said casings each having a door 9 with apertures 10 therein to admit water. 55

Within the casing is a wire cage 11 supported by the insulations 12 and the cage constitutes a conductor of electricity to which one of the lead wires or conductors 13 is connected whereas another conductor or 60 lead wire 14 which is utilized for completing a circuit is connected in any appropriate way to a pendulum 14^a which is loosely mounted in the said cage. The lower end of the pendulum 14^a has a float 15 preferably a hollow 65 metallic ball secured to it so that when water enters the casing, the ball rises therein to cause the contact shoulder 16 which is preferably of disk form secured in any suitable manner to the pendulum to engage the wires 70 of the cage, thereby establishing an electrical contact which will complete the circuit to be hereinafter described.

The pendulum is supported in the cage by the stem 17 having a head 18 of non-conducting material so that under normal conditions, the pendulum may hang in the cage in position to be actuated under the influence of the float. 75

The pendulum is furthermore so positioned with relation to the cage that if the bridge should become impaired to the extent that it would lean, be inclined, or break, the pendulum would come in contact with the wires of the cage and close the circuit. 80 85

I claim—

A circuit closer comprising a casing, a cage which constitutes one contact, mounted in said casing but insulated therefrom, and a metallic pendulum constituting the other 90 contact, supported from the top of the cage and insulated therefrom, said pendulum being free to swing into engagement with the cage when the cage is inclined, and a float connected to said pendulum for raising the 95 pendulum into engagement with the cage to establish a circuit.

GEORGE W. WASHINGTON.
